UNITED STATES PATENT OFFICE.

BENJAMIN E. GETZ, OF MORTON, ILLINOIS.

FUEL-BURNING SYSTEM.

Application filed April 18, 1925. Serial No. 24,080.

This invention relates to a liquid fuel burning system designed to use any of the well known combustibles, such as, fuel oil, gas oil, distillate, kerosene or gasoline, and 5 of the type capable of being used preferably as a heating plant for homes or commercial buildings, including a fuel reservoir located preferably underground and above the plane of the burner and a fuel supply line connecting the reservoir, suction and pressure pump, and atomizer and air lines communicating with said fuel line.

10 The invention has for one of its objects to provide in a liquid fuel burning system an air line in communication with the fuel line and including valve means for regulating the volume of air to the fuel line, whereby to control the consumption of fuel and the siphonic-action in the system.

15 20 The invention has for a further object the provision of means in the fuel line to intercept the flow of the fuel therein by the admission of air, resulting in breaking up the fuel flow and causing the same to be 25 conveyed to the burner under slight pressure, which is not unlike in purpose and object the subject matter included in an application filled by me on or about February 2, 1925 for improvements in a fuel burning 30 system bearing Serial No. 6,248.

The invention has for a still further object to provide in a liquid fuel burning system a suction and pressure pump, an air pump and an atomizer; the suction and pressure 35 fuel pump being connected by a supply line with the source of supply and to an air line having a controlling means therein; said suction and pressure pump and said air 40 pump being connected with the atomizer through fuel and air supply lines, a connection being made between the latter two lines, the fuel line of which at the point of introduction of air therein being provided with 45 means intercepting the fuel and air, to break up the flow of fuel and to apply a pressure of air thereto, which minimizes the consumption of fuel and presents it to the atomizer in a more perfect state.

50 The invention further comprehends a liquid fuel burning system designed for heating purposes in the home or elsewhere, comprising a fuel reservoir located preferably underground and at a distance from the burner, although it is to be understood that it may be located in the basement of a dwelling or elsewhere, provided with a fuel sup-

ply line leading from the fuel reservoir to a suction and pressure pump located preferably within the building or dwelling, the fuel line being intercepted at some intermediate point preferably within the building or dwelling by an air line having a control means therein; the fuel line extending from the suction and pressure pump and communicating with a coupling into and 60 through which the liquid fuel is caused to pass and into a fuel line terminating in an atomizer located preferably within the heater or furnace; an air pressure pump having a more or less direct communication with 65 the atomizer by means of an air line and intercepted in its length by a communicating air pipe having connection to said coupling through which air is caused to pass and intermingle with the fuel on its passage to the 70 atomizer.

75 That the invention may be more fully understood, reference is had to the accompanying drawings, illustrating a preferred embodiment of the invention and forming 80 a part of this description, in which:—

Figure 1 is a more or less diagrammatic elevation, partly in section, showing my improved liquid fuel burning system;

Figure 2 shows in a side elevation the arrangement of the air and fuel pumps in connection with the air and fuel lines terminating in the atomizer;

Figure 3 is a side elevation, partly in section, of the air pressure pump;

Figure 4 is a cross-sectional view of the coupling in the fuel and air lines providing for the intermixture of the air and liquid fuel;

Figure 5 is a cross-sectional view of the 95 atomizer showing the air and fuel channels, and

Figure 6 is a detail of a preferred construction of an air valve in the air line.

Like characters of reference denote corresponding parts throughout the figures.

In Figure 1 a fuel reservoir or container 1 is shown preferably located underground and outside of a building or dwelling 2. Connected near the top of the reservoir 1 an air vent 3 is provided for the ingress 105 and egress of air to the outside atmosphere. Depending within the reservoir 1 to within a short distance from the bottom thereof is a fuel supply pipe or line 4 which is connected to the top of the reservoir and by means of an L 5 the pipe or line 4 takes 110

preferably a horizontal direction through the wall 6 of the building or dwelling where by means of a T 7 the fuel pipe or line 4 takes a downwardly direction and is attached to a rotary gear fuel pump 8 of the usual design capable of creating a suction on one side and a pressure on the other.

Connecting preferably with the upper portion of the T 7 is an air line or pipe 9 of any desired length, however, it is desirable to have said line or pipe terminate at a point near the furnace or heater to be within easy reach of an attendant, and at or near the terminus of said line or pipe, the same is provided with a controlling and regulating valve 10, the purpose of which will be further explained.

Leaving the fuel pump 8 on the pressure side thereof, the fuel line or pipe 4 takes 20 preferably a horizontal direction to an L 11 where it is directed upwardly and is attached to the coupling 12, to be more fully described. The fuel line or pipe 4 leaves the discharge end of the coupling 12 and 25 by means of the L's 13 and 14 takes preferably a horizontal direction and by suitable connections is attached to the atomizer 15 which is preferably located within the furnace or heater 16, shown in dotted lines in 30 Figures 1 and 2.

A suitable source of power, preferably shown by means of an electric motor 17 including a driving belt 18 suitably connected to the air pressure pump or blower 19, see 35 Figure 1, is used to operate the air pump 19 and fuel pump 8. Within the housing or casing 20 of the air pump 19 are suitably mounted air vanes 21 on the driving shaft 22, see Figure 3, and which supply a pressure of air from the pipe opening 23 out through the discharge opening 24 into the air line or pipe 25, to be more fully described. Suitably mounted within the supply pipe opening 23 of the air pump or 40 blower 19 is an adjustable valve 26 provided with a hand lever 27 for controlling the ingress of air into the air pump or blower 19, as desired. The suction and pressure fuel pump 8 derives its operation 45 through the extension of the driving shaft 22 of the air pump or blower 19 upon which is provided a toothed gear 28 which acts in co-operation with another similar toothed gear 29, which when in operation creates a 50 sufficient suction in the fuel line 4 as to cause fuel to be supplied from the reservoir 1 to the fuel pump 8, and further to create a sufficient pressure as to cause the liquid fuel to be forced through the fuel line or pipe and 55 pipe connections to the atomizer 15, as will be understood.

Connected to the discharge opening of the air pressure pump or blower 19 is an air pipe or line 25, previously referred to, which is connected directly to the atomizer 15, see

Figures 1, 2 and 5, and communicating with the air pipe or line 25 is a short pipe or line 30 which is connected to the coupling 12 through which air is caused to pass, being supplied by the air pump or blower 19.

70

The coupling 12, best seen in Figure 4, is shown provided with the air pipe or line 30 secured to one end and on its underneath side is secured the fuel line or pipe 4, the fuel pipe or line 4 being also secured to the

75

discharge end of the coupling 12 opposite the air pipe or line 30. Provided in the interior of the coupling 12 and in the plane of the air pipe or line 30 and discharge fuel pipe or line 4 is a short nozzle 31 extending horizontally of the coupling and slightly in advance of the fuel pipe or line 4 which has

80

connection on the underneath side thereof. It will be understood that liquid fuel upon entering the coupling 12 through the opening 85 on the underside thereof will of necessity be caused to enter the fuel line or pipe 4 leading therefrom due to the pressure of air from the air pipe or line 30 passing through

90

the nozzle 31 which intermingles with the liquid fuel and also tends to pick up or aid the same through the fuel line or pipe 4 to the atomizer 15. The liquid fuel burning systems now in use which employ a suction and pressure pump to supply the fuel

95

burner with liquid fuel have experienced more or less difficulty in obtaining an even flow of fuel through the fuel lines to the point of consumption. The most common

100

complaint in this regard has been that the liquid fuel would flow in spurts through the fuel lines causing the burner to burn unevenly and at times even be extinguished, causing a fire hazard. The coupling 12 is

105

designed to remedy this condition and it will be understood, that the liquid fuel gaining entrance to the coupling 12 would be gurgling and spouting past the nozzle 31 in uneven amounts, however, a pressure of air supplied to the coupling 12 by means of the

110

air line 30 would be discharged within the coupling 12 through the nozzle 31 and be intermingled with the liquid fuel with the result that the liquid fuel is supplied to the atomizer 15 in an even stream and under a slight pressure due to the air pressure intermingled with the fuel.

115

In Figure 5 the atomizer 15 is shown having an air supply pipe or line 25 communicating rearwardly of the same with an upstanding annular air chamber or recess 32 which has connection with a diagonally disposed recess or chamber 33 communicating with the front face of the atomizer

120

preferably near the center thereof. The fuel line or pipe 4 is connected to the atomizer 15 preferably centrally of the same communicating with a short horizontal fuel opening or channel 34 which terminates in the front

125

face of the atomizer and preferably adja-

130

cent to the air channel or recess opening 33. It will be clearly understood, that a pressure of air from the air pipe or line 25 introduced into the atomizer 15 by means of 5 the air chamber or recess opening 32 will enter the diagonally disposed channel 33, as indicated by the directional arrows in Figure 5. It will be also understood that a supply of liquid fuel from the reservoir 1 supplied 10 to the atomizer would gain entrance to the same by means of the fuel pipe or line 4 and the small horizontal channel 34, as indicated by the directional arrows. It will be seen that a pressure of air and intermingled 15 liquid fuel coming out from the atomizer by means of the openings 34 and 33, respectively, that a complete atomization of the liquid fuel is accomplished and prepared in a perfect state for proper combustion.

20 Assuming the fuel reservoir 1 to be filled with liquid fuel, the operation of the fuel system is as follows:—Closing the regulating or controlling air valve 10 and starting the electric motor 17, it will be understood 25 that the fuel pump 8 will suck liquid fuel from the fuel reservoir 1 through the fuel line 4 to the fuel pump and due to its construction, cause the fuel to be pumped under a sufficient pressure to the coupling 12 30 where the liquid fuel is met by a stream of air under pressure supplied by means of the air pressure pump 19 and air connections 25 and 30, which intermingles with the liquid fuel and aids the passage of the same to the atomizer 15. It will be further understood 35 that the air line or pipe 25 having a direct communication with the rear face of the atomizer from the air pump 19 supplies air which completes the atomization of the liquid fuel. After the system has been started 40 the regulating or controlling air valve 10 is opened slightly which introduces a supply of air into the fuel line 4, as shown in Figure 1 by means of the coupling 7, and which, it 45 will be understood, serves to further regulate the atomization of the fuel. The regulation of the air valve 10 is preferably determined upon the installation of the system and is set preferably at a point where 50 the introduction of air in the system will serve to minimize the consumption of fuel and yet obtain the greatest amount of heat units therefrom. It is not intended that the air valve 10 need be adjusted each time the system is in operation for after once set at 55 the desired point, will serve as already explained.

The air valve 10 has a further purpose and function and it will be readily seen that 60 after being once regulated that upon the stopping of the fuel system, either manually or by automatic control means, that the possibility of the liquid fuel being siphoned from the reservoir 1 is made impossible due 65 to the fact that air gaining entrance to the

fuel line 4 by means of the regulating and controlling air valve 10 would prohibit the passage of liquid fuel from the reservoir 1 through the fuel system until caused to circulate by means of the fuel pump 8, being 70 started manually or by thermostatic control, as is generally customary.

I prefer to construct the air valve 10 so that it cannot be completely closed, thereby 75 permitting air to enter and circulate through the air pipe 9 and through the system, which will prevent siphoning of the fuel through the fuel line on the stoppage of the pressure means.

What I claim is:—

1. In a liquid fuel burning system for heating purposes, in combination, a reservoir for containing liquid fuel, a pump, a burner, a fuel line connecting the reservoir and the burner, an air line in communication with the fuel line above the level of the reservoir, and controlling means to vary the volume of air admitted to the fuel line and formed to constantly permit a predetermined quantity of air to flow therethrough whereby 80 to break the siphon of the fuel line upon stoppage of the pump.

2. In a liquid fuel burning system for heating purposes, in combination, a burner, a reservoir for containing liquid fuel, a fuel line connecting the reservoir with the burner, a pressure means in the fuel line having an intake and a discharge, an air line in communication with the fuel line above the level of the reservoir on the intake side of said pressure means, and an adjustable controlling means in the air line for controlling the volume of air admitted to the fuel line and formed to constantly permit a predetermined quantity of air to flow therethrough 95 thereby to control the volume of fuel admitted to the burner.

3. In a liquid fuel burning system for heating purposes, in combination, a burner, a reservoir for containing liquid fuel, a fuel line connecting the reservoir with the burner, a pressure means in the fuel line having an intake and a discharge, an air line in communication with the fuel line on the intake side of said pressure means and at an elevation above the normal fuel level in the reservoir, and an adjustable controlling means in the air line for controlling the volume of air admitted to the fuel line and formed to constantly permit a predetermined quantity 110 of air to flow therethrough thereby to control the volume of fuel admitted to the burner.

4. In a liquid fuel burning system for heating purposes, in combination, a burner, a reservoir for containing liquid fuel, a fuel line connecting the reservoir with the burner, a pressure means in the fuel line having an intake and a discharge, an air line in communication with the fuel line on the intake side of said pressure means, an air pressure 125

means, an air line connecting the air pressure means with said burner and in communication with said fuel line on the pressure side of said pressure means, and an ejector in the fuel line at the juncture of said last mentioned air line with said fuel line.

5. In a liquid fuel burning system for heating purposes, in combination, a burner, a reservoir for containing liquid fuel, a fuel line connecting the reservoir with the burner, a pressure means in the fuel line having an intake and a discharge, an air line in communication with the fuel line on the intake side of said pressure means and at an elevation above the normal fuel level in the reservoir, an air pressure means, an air line connecting the air pressure means with said burner and in communication with said fuel line on the pressure side of said pressure means, and an ejector in the fuel line at the

juncture of said last mentioned air line with said fuel line.

6. In a liquid fuel burning system for heating purposes, in combination, a burner, a reservoir for containing liquid fuel, a fuel line connecting the reservoir and the burner, a pressure means in said fuel line, an air line in communication with the fuel line above the level of the fuel in the reservoir, and an adjustable controlling means in the air line for controlling the volume of air admitted to the fuel line and formed to constantly permit a predetermined quantity of air to flow therethrough, thereby to control the volume of fuel admitted to the burner and to break the siphon in the fuel line on the cessation of the pressure means.

In witness whereof, I have hereunto affixed my hand this 15th day of April, 1925.

BENJAMIN E. GETZ.
